HAROLD W. MATTINGLY, OF SWISSVALE, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed February 4, 1929. Serial No. 337,314.

My invention relates to relays and more particularly to inductor relays of the type employed in control circuits for elevators, hoists and similar equipment.

5 In elevator installations, it is common to provide holding circuits for the various direction-switches and speed switches, which circuits are opened automatically in any selected order by inductor relays carried by 10 the car operated, when their magnets are energized, as they are moved past magnetizable iron inductor plates stationarily mounted in the hatchway at suitable distances from the floor levels past which the car moves. A system 15 of this type is disclosed in the copending application of Edgar M. Bouton, Serial No. 731,921, filed August 14, 1924 and assigned to the Westinghouse Electric and Manufacturing Company.

20 The inductor relays operate to stop the car at the floor levels at all of the floors intermediate the terminals but additional stopping devices must be provided for stopping the car at the terminal floors since absolutely 25 positive action is necessary at these points for safety reasons and it is not desirable to depend upon the energized condition of a magnet for stopping the car when failure would mean danger to passengers and equipment.

30 In the past, it has been the practice to provide, in addition to the usual inductor relays for stopping the car, a separate terminal stopping switch, carried by the car, to be mechanically moved to its circuit controlling position by cams mounted at the terminals of the hatchway.

Such arrangement however, means that 35 space on the car structure must be provided for the terminal switches as well as additional weight added to the car structure. Moreover, the terminal switch must be connected in its circuits by wiring installed in the field rather than in the manufacturing plant.

It is, therefore, an object of my invention 40 to provide means for automatically magnetically slowing down and stopping the car at intermediate floors which shall be integrally combined with mechanical means

for slowing down and stopping the car at either terminal.

Another object of my invention is to provide a relay that shall combine the properties of a mechanical safety device and an automatic magnetic stopping device. 55

More specifically stated, the object of my invention is to provide an inductor relay, the contact members of which may be operated either by a magnetic circuit or by mechanical means. 60

Another object of my invention is to provide a switch which combine, in a unitary structure, a magnetically operated switch and a mechanically operated switch which 65 may be assembled in the factory and installed as a unit, obviating the necessity of separate wiring for separate switches.

I have illustrated one of the various forms my invention may take, and one of the various 70 applications thereof in the accompanying drawings, in which,

Figure 1 is a view, in perspective, of an inductor relay embodying my invention, and

Fig. 2 is a diagrammatic view of a control 75 scheme for an elevator system embodying my inductor relay.

Referring to the drawings, I have illustrated, in Fig. 1, a relay 10 designed to be mounted upon and carried by the elevator car structure to move therewith past the floors which it serves. The relay illustrated herein is an inductor relay of the general type disclosed in the copending application of H. W. Williams, Serial No. 279,771, filed May 22, 1928 and assigned to the Westinghouse Electric and Manufacturing Company, and comprises a suitable base 11, secured to which is a coil 12 which is provided with large rectangular end plates 13 and 14 of suitable magnetic material. A plate 15, of insulating material, is mounted upon the rear edges of the end plates 13 and 14 to brace them in their operating positions and also to provide a terminal board for the electrical connections 80 of the relay. 85

As shown, the relay is provided with four pairs of cooperating armatures 16 and 17, 18 and 19, 20 and 21, and 22 and 23, that are 90 pivotally supported upon the end plates 13 100

and 14 by means of pivot pins 24. In order that each armature may be employed to open or close a circuit, it is provided with an arm 25 of insulating material which carries a contact member 26 disposed to engage a cooperating contact member 27 on a stationary conducting arm 28 that extends from the panel board or plate 15. The contact members 26 and 27 are biased to a closed position by tensile springs 29 which are mounted between, and attached to, the extending arms 25 of each pair of armatures.

An inductor plate 30, of iron or other magnetizable material, stationarily mounted upon some part of the hatchway structure, is so positioned as to enter the space between cooperating pairs of armatures 16-18 and 17-19 as the car passes the inductor plate. Hence the magnetic circuit, normally extending from the upper end of coil 12 through armatures 16 and 18 and thence through the air gaps between armatures 16 and 17, and 18 and 19 to the lower end of coil 12 will be changed by the insertion of inductor plate 30 in place of the large air gaps to thereby allow the magnetism produced by coil 12 to overcome the force of springs 29 and cause the armatures to move and open their respective contact members.

Contact members 26 and 27 associated with armature 16 and contact members 31 and 32, associated with armature 18, constitute, in effect, a "double break" switch by having a current conducting shunt 33 connected between contact members 26 and 31 respectively. Hence if a circuit to be controlled by the relay 10 is connected to stationary arms 28 and 34, movement of either armature 16 or 18 will open the circuit.

The contact members for armature pairs 17-19, 20-22 and 21-23 are similarly arranged for controlling respective circuits connected to each pair.

Another inductor plate 35 is provided in alignment with the openings between armatures 20-22 and 21-23 for actuating these armatures when the car passes the inductor plate. By connecting different circuits to each armature pair, and disposing the inductor plates 30 and 33 at different distances from the floor levels, the circuit may be controlled in any desired sequence as is herein-after described.

The armature members 16 and 17, 22 and 23 are each provided with a roller 36, rotatably mounted, by means of a pin 37, on a member 38 (preferably of non-magnetic material) which is in turn connected in any suitable manner, as by screws 39, to its associated armature member.

By arranging cam members of suitable length at the ends of car travel, to engage rollers 36 on the respective armatures 16, 17, etc., it is apparent that the associated armatures will be moved to open the circuit con-

trolled thereby in a positive manner, whether the magnet coil 12 is energized or not. By this arrangement the same switch which is actuatable magnetically by the inductor plates may also be actuated mechanically to open the desired circuits.

Referring again to the drawings, Fig. 2 shows a motor-generator-motor set of the Ward Leonard type comprising a driving motor M having a field winding MF and an armature M' directly coupled to drive a generator G. An elevator motor EM, directly connected to a hoisting drum D, has its armature EM' connected in "loop" circuit with the armature G' of the generator G and the series field winding GSF of the generator G. In addition to the series field winding GSF, the generator G is provided with a separately excited field winding GF, and an auxiliary demagnetizing field winding GAF. The elevator motor EM is shown as separately excited, its field EMF being connected directly across line conductors L₁ and L₂.

An elevator car C, is connected to, and partially balanced by a counterweight CW, by means of a cable Ca which passes over the hoisting drum D.

For maintaining the motor speed constant under varying loads, the series winding GSF of the generator G is so proportioned that cumulative compounding of the generator is achieved to increase the voltage supplied to the motor under increase in load, and to decrease the voltage supplied to the motor under light or overhauling loads in such proportions as to counteract the normal characteristic of the elevator motor to decrease its speed as the load increases.

The direction and speed of rotation of the elevator motor is controlled by an up-direction switch 1, a down direction switch 2, and speed relays 3 and 3'. The directional switches 1 and 2 control the direction of current flow through the separately-excited-generator-field winding GF, and the speed relay 3 controls the current value by including or excluding a resistor R from the circuit of the separately-excited-generator-field winding GF. The deceleration and stopping of the car is automatically controlled by means of an up-direction high-speed inductor relay UR, a down-direction high-speed inductor relay DR, an up-direction slow-speed inductor relay URS, a down-direction slow-speed inductor relay DRS, mounted on the car cooperating with inductor plates disposed in the hatchway adjacent the intermediate floor.

The illustrated system is shown as serving three floors, the intermediate of which, or second floor, has associated therewith an inductor plate for each inductor relay, so mounted with reference to the floor level as to magnetically actuate the relay contact members at the instant the car passes to the proper point for initiation of slow down or

for final stopping as will cause the car to stop accurately at the floor level without overrunning or under-running the floor. The plates are designated with a primed reference character corresponding to the reference character allotted to the relay it controls. While for simplicity of drawing, the relays are indicated as separate, it is to be understood that the relays may consist of separate pairs of contact members and armatures, all of which may be controlled by the same coil, as is illustrated in Fig. 1. For example UR may be armatures 17-19, DR may be armatures 16-18, URS may be armatures 21-23 and DRS may be armatures 20-22.

At the terminal floors (the first and third), however, cam members UR'' and URS'', DR'' and DRS'' are substituted for the inductor plates UR', etc., and are so positioned as to mechanically actuate the armatures to the respective relay members UR etc., when the car arrives at the upper or lower terminals. By disposing the rollers 36 associated with armatures 16 and 17 out of vertical alignment, there need be no interference between contact members in the "down" circuits and in the "up" circuits.

The application of my invention is best discussed by means of an assumed elevator operation. Let it be assumed that the car is at the lower terminal, and that it is desired that the car shall proceed to the second floor, stop there, and then proceed to the upper terminal.

To start the car, the operator moves the handle of a car switch Cs in a clockwise direction to complete a circuit for energizing up-direction switch 1, which circuit extends from line conductor L₁, through conductor 41, contact members 42, 43 and 44 of the car switch CS, conductor 45, the coil of up-direction switch 1, conductor 46, contact members 47 of stopping inductor relay URS, and conductors 48 and 49 to line conductor L₂. Upon closing, up-direction switch 1 completes a self-holding circuit for its coil which extends from line conductor L₁, through conductors 50 and 51, contact members d of up-direction switch 1, conductors 52 and 45, the coil of up-direction switch 1, and thence as previously traced to line conductor L₂.

Upon closing, up-direction switch 1 completes another circuit for the separately-excited-generator field winding GF which circuit extends from line conductor L₁, through conductors 50 and 53, contact members b of up-direction switch 1, conductors 54 and 55, the resistor R, conductor 56, the separately-excited-generator-field winding GF, conductors 57 and 58, contact members a of up-direction switch 1, and conductor 59 to line conductor L₂.

The generator G now has field excitation sufficient to cause it to supply sufficient voltage to the elevator motor EM to cause the mo-

tor to accelerate to, and run continuously at, an intermediate speed, as determined by the value of resistor R. The elevator car C, therefore, starts upwardly.

To accelerate the car to full speed, the attendant moves the car switch handle further to the right to complete a circuit for the coil of speed relay 3, which circuit extends from line conductor L₁, through conductor 41, contact members 42, 43 and 60 of the car switch CS, conductor 61, the coil of relay 3, conductor 62, the contact members 63 of inductor relay UR, conductors 64 and 49 to line conductor L₂. Upon closing, relay 3 completes a holding circuit for its coil extending from line conductor L₁, through conductors 50 and 65, contact members a of relay 3, conductor 66, the coil of relay 3, and thence as previously traced to line conductor L₂.

Upon closing, relay 3 short circuits the resistor R from the circuit of the separately excited generator field winding by way of its contact members b and conductors 67 and 68.

The generator voltage consequently rises, the motor speed increases and the car accelerates to full speed.

As the car approaches the floor at which it is to stop, the operator returns the car switch handle Cs to its original off position, thereby completing a circuit for the coils of relays UR and URS, extending from line conductor L₁, through conductor 41, contact members 42, 43 and 69 of the car switch Cs, conductors 70 and 71, the coil of relay URS, conductor 72, the coil of relay UR, conductor 73, contact members e of up-direction switch 1, conductors 74, 75 and 59 to line conductor L₂.

As inductor relay UR passes its associated inductor plate, located in the hatchway adjacent the second floor, it operates to disengage its contact members 63, thereby opening the circuit for the coil of relay 3. As relay 3 drops out the resistor R is reinserted into the circuit of the separately excited generator field winding, and the generator field excitation decreases. The generator G now supplies the elevator motor EM with voltage only sufficient to operate it at an intermediate speed as determined by resistor R. The car therefore decelerates.

As inductor relay URS passes its associated inductor plate, it operates to disengage its contact members 47, thereby opening the circuit for the coil of up-direction switch 1. As up-direction switch 1 drops out, the circuit for the separately excited generator field is opened, and the circuit for the auxiliary field winding GAF is completed through contact members c on the up direction switch 1.

The auxiliary field winding GAF is connected directly across the generator terminals, being controlled by the directional switches, by way of a circuit extending from conductor 76, through the auxiliary winding GAF, conductor 77, normally closed contact mem-

bers *c* of down-direction switch 2, conductor 78, normally closed contact members *c* of up direction switch 1, and conductor 79 to conductor 80, and it is so designed that it sets up a field equal and opposite to that set up by the generator series field winding and the residual magnetism in the generator iron.

The generator voltage, therefore, decreases to zero, and the motor comes to a stop, through 10 regenerative braking, as the car comes level with the floor. A magnetic brake, (not shown) effects final stoppage, and holds the elevator motor stationary until the car switch is again operated.

15 In order to continue to the terminal floor the operator will again proceed as described above.

As the car approaches the terminal floor, the inductor relay UR engages its associated 20 cam "UR", thereby disengaging its contact members 63. As before, the disengagement of the contact members 63 of relay UR drops out relay 3, which results in the reinsertion of resistor R into the separately excited generator field circuit, and the elevator decelerates.

25 Similary, as the inductor relay URS engages its associated cam "URS", its contact members 47 are disengaged and the car comes to rest as previously described.

30 Although this description has been limited to travel in the up direction only, it is apparent that travel in the down direction would be similarly controlled except that up-direction switch 1, speed relay 3 and inductor 35 relays UR and URS and their cams would be replaced by down-direction switch 2, speed relays 3' and inductor relays DR and DRS and their cams.

In order that the relay may function as a 40 safety device, it must operate to stop the car at the terminal floors regardless of the position of the car switch handle. Should the operator fail to return the car switch handle to its normal position as the car approaches 45 either of the terminals, the coils of the inductor relays will not be energized. Therefore, although the cams would operate to disengage the relay contact members as soon as the relay was out of range of the cam there 50 would be no means to keep them open, and they would close, thereby recompleting the associated circuit. I have therefore provided that the cam associated with the relay UR shall be extended to engage the roller of 55 relay UR until the cam associated with relay URS shall engage the roller of relay URS; and that the cam associated with relay URS shall be extended to engage the roller of URS until the car moves away from the terminal. 60 The cams associated with relay DR and DRS are similarly extended.

65 It will be seen therefore that I have devised an inductor relay adapted to be operated either mechanically or magnetically, and that I have applied it to an elevator con-

trol system in such a way as to provide magnetically controlled slow down and stop of the elevator car at intermediate floors; and automatic, mechanically effected, slow down and stop at terminal floors. My invention 70 combines the properties required for normal operation and for a safety device, thereby eliminating the regular safety switch and its attendant wiring.

While I have illustrated and described only 75 one embodiment of my invention, I realize that it is susceptible of wide application, and do not therefore wish to be limited to the combination described except as set forth in the 80 appended claims.

I claim as my invention:

1. In an elevator system, an elevator car operable in a hatchway between limit positions; motive means for said car; a switch for controlling said motive means to stop said car; a control circuit; an electromagnetic operator for said switch, effective to operate said switch when said circuit is in a predetermined condition of energization, and said car is in a predetermined position between said limit positions; and a mechanical operator for operating said switch to stop said car in a limit position, regardless of the operative condition of said circuit.

2. In an elevator system, an elevator car operable in a hatchway between limit positions; motive means for said car; a switch for controlling said motive means to stop said car; an electromagnetic operator for said switch comprising a winding and relatively 85 movable magnetic elements, controlled by the movement of said car, said operator being effective to operate said switch when said winding is in a predetermined condition of energization, and said car is in a predetermined position between said limit positions; electrical control means for establishing said 90 predetermined condition of energization of said winding to initiate a stopping operation of said car when it is in said predetermined position; and a mechanical operator for operating said switch to stop said car in a 95 limit position, regardless of the operative condition of said electrical control means.

3. In an elevator system, an elevator car operable in a hatchway between limit positions; motive means for said car; a switch mounted upon said car for controlling said 100 motive means to stop said car; an electromagnetic operator for said switch comprising a winding and a magnetic element mounted upon said car and a magnetic element 105 mounted in the hatchway, said operator being effective to operate said switch when said winding is in a predetermined condition of energization, and said car is in a predetermined position between said limit positions; electrical control means for establishing said 110 predetermined condition of energization of said winding to initiate a stopping operation of said car when it is in said predetermined position; and a mechanical operator for operating said switch to stop said car in a limit position, regardless of the operative condition of said electrical control means.

115 4. In an elevator system, an elevator car operable in a hatchway between limit positions; motive means for said car; a switch mounted upon said car for controlling said motive means to stop said car; an electromagnetic operator for said switch comprising a winding and a magnetic element mounted upon said car and a magnetic element 120 mounted in the hatchway, said operator being effective to operate said switch when said winding is in a predetermined condition of energization, and said car is in a predetermined position between said limit positions; electrical control means for establishing said 125 predetermined condition of energization of said winding to initiate a stopping operation of said car when it is in said predetermined position; and a mechanical operator for operating said switch to stop said car in a limit position, regardless of the operative condition of said electrical control means.

tion of said car when it is in said predetermined position; and a mechanical operator for operating said switch to stop said car in a limit position, regardless of the operative condition of said electrical control means.

4. In an elevator system, an elevator car operable in a hatchway between limit positions; motive means for said car; a switch for controlling said motive means to decelerate said car; an electromagnetic operator for said switch comprising a winding and relatively movable magnetic elements, controlled by the movement of said car, said operator being effective to operate said switch when said winding is in a predetermined condition of energization, and said car is in a predetermined position between said limit positions; electrical control means for establishing said predetermined condition of energization of said winding to initiate a decelerating operation of said car when it is in said predetermined position; and a mechanical operator for operating said switch to initiate a decelerating operation of said car when it is in a predetermined position in advance of a limit position, regardless of the operative condition of said electrical control means.

In testimony whereof, I have hereunto subscribed my name this 31st day of January, 1929.

HAROLD W. MATTINGLY.
